United States Patent Office

Des. 232,809
Patented Sept. 17, 1974

232,809

BOTTLE

John Pardo, Yonkers, N.Y., assignor to The Procter & Gamble Company, Cincinnati, Ohio

Filed Oct. 11, 1972, Ser. No. 296,658

Term of patent 14 years

Int. Cl. D9—01

U.S. Cl. D9—45

FIG. 1 is an elevational view of a bottle showing my new design;

FIG. 2 is an elevational view looking from the right of FIG. 1;

FIG. 3 is a sectional view taken on the line 3—3 of FIG. 1; and

FIG. 4 is a sectional view taken on the line 4—4 of FIG. 1.

The sides opposite those shown in FIGS. 1 and 2 are the same as the sides shown.

I claim:

The ornamental design for a bottle, as shown and described.
